UNITED STATES PATENT OFFICE.

GEORGE L. PREBLE, OF LYNN, MASSACHUSETTS.

INSOLE.

1,018,132.

Specification of Letters Patent. Patented Feb. 20, 1912.

Application filed May 1, 1911. Serial No. 624,322.

To all whom it may concern:

Be it known that I, GEORGE L. PREBLE, of Lynn, in the county of Essex and State of Massachusetts, have invented certain new and useful Improvements in Insoles, of which the following is a specification.

This invention relates to insoles composed of a plurality of layers of different materials.

10 A common form of insole now in extensive use is composed of a layer of woven material and a layer of leather, the two layers being attached one to another by cement. The layer of woven material is creased to form a stitch-receiving rib, and it is customary to inclose in the crease a strip of suitable material, such as stout cord, for the purpose of reinforcing the stitch-receiving rib. An insole composed 20 of layers cemented together in this way is oftentimes inefficient, because a relatively slight strain is sufficient to pull apart the layers which are joined solely by cement.

25 The object of the present invention is to provide a composite insole of which the layers are composed of materials which may be united and which when united will be substantially inseparable, however great may be the strain tending to pull them 30 apart.

The essential elements of an insole constructed in accordance with this invention are: a layer of textile material and a layer of celluloid. The textile material is provided with the usual crease to form the stitch-receiving rib, and the celluloid laid against the opposite side of the textile material with relation to the rib is interlocked with the fibers of the textile material by 35 subjecting it to any suitable solvent and by pressing the layers together while the celluloid is somewhat soft and plastic. A reinforcing strip of fibrous material may or may not be placed in the crease of the textile material, as desired. If such reinforcing strip is used, it is directly united with the celluloid by the same process which unites the celluloid with the layer of textile material. The reinforcing strip is therefore not only held in place by the layer of 45 textile material, but is held independently thereof by the celluloid itself. When the celluloid hardens after being pressed into the spaces between the fibers of the textile material, the layers are so firmly inter-

locked that it is impossible to pull them apart without tearing the fibrous material.

Of the accompanying drawings which illustrate the invention: Figure 1 represents a bottom plan view of an insole. Fig. 2 represents an enlarged cross section of one edge thereof. Fig. 3 represents a longitudinal section of a portion of the insole, to which are added a sock lining and a shank stiffener. Fig. 4 represents a perspective view of the sole, a part of the celluloid being broken out to show the layer of textile material and the reinforcing strip.

The same reference characters indicate the same parts wherever they occur.

70 The layer of textile material is indicated at 10, and the layer of celluloid is indicated at 11. The celluloid is interlocked with the textile material as represented by the sectional views. The textile material is creased to form a stitch-receiving rib 12. As shown by Figs. 2 and 4, a reinforcing strip 13 is laid in the crease of the rib. The celluloid 11 is directly interlocked with the fibers of the strip 13. An insole comprising the 80 foregoing elements assembled in the manner described is complete for some kinds of footwear, the layer of celluloid being sufficiently flexible to afford comfort to the wearer and being a sufficient sock lining. 85

To the foregoing elements may be added, when desired, a shank stiffening member such as that indicated at 14 in Fig. 3. When a stiffening member is used, it is desirable to add also another layer 15 of 90 material suitable for a sock lining. Woven material is suitable for this purpose. When the member 14 and layer 15 are to be used, the member 14 is interposed between the celluloid and the layer 15. The layer 15 95 directly engages the celluloid in the fore-part of the sole and is interlocked with the celluloid in the same manner as the layer 10. The celluloid may also be interlocked with the fibers of the stiffening member 14 by applying a suitable solvent to the celluloid before pressing the stiffening member against it. A coating 16 of cement is used 100 to unite the stiffening member 14 and the lining 15.

105 An insole composed of the aforesaid elements is not only strong, but is waterproof and moisture-proof. The layer of celluloid intervening between the foot of the wearer and the leather sole not only prevents the 110

admission of moisture from without, but insulates the leather sole from the foot so that perspiration from the foot will not reach the leather sole and cause rotting of the leather, and the usual odor caused thereby.

I claim:

1. As an article of manufacture, an insole comprising a layer of textile material having a crease, a strip of fibrous material in said crease, and a layer of celluloid interlocked with said layer of textile material and with said strip.
2. As an article of manufacture, an insole

comprising a layer of textile material having a stitch-receiving rib, a layer of suitable material, an intermediate layer of celluloid interlocked with the first-mentioned layers whereby they are joined together, and a shank stiffener of fibrous material between said first mentioned layers and interlocked with said layer of celluloid.

In testimony whereof I have affixed my signature, in presence of two witnesses.

GEORGE L. PREBLE.
